(57) **CLAIM**

The ornamental design for an anaphylaxis treatment kit external, as shown and described.

DESCRIPTION

FIG. 1 is a front view of an anaphylaxis treatment kit external in accordance with the new design;

FIG. 2 is rear view of the anaphylaxis treatment kit external of FIG. 1;

FIG. 3 is a left side view of the anaphylaxis treatment kit external of FIG. 1;

FIG. 4 is a right side view of the anaphylaxis treatment kit external of FIG. 1;

FIG. 5 is a top plan view of the anaphylaxis treatment kit external of FIG. 1;

FIG. 6 is a bottom plan view of the anaphylaxis treatment kit external of FIG. 1;

FIG. 7 is a front perspective view of a anaphylaxis treatment kit of FIG. 1;

FIG. 8 is rear perspective view of the anaphylaxis treatment kit external of FIG. 1; and,

FIG. 9 is a front perspective view of the anaphylaxis treatment kit external of FIG. 1 with a key thereof shown displaced from a keyhole thereof.

The broken lines in the figures illustrate portions of the anaphylaxis treatment kit external which form no part of the claimed design.

1 Claim, 9 Drawing Sheets
